TRAVELER REPLACING APPARATUS
AND METHOD

Edward E. Eurey, Newberry, S.C., assignor to Excel, Inc.,
Lincolnton, N.C., a corporation of North Carolina
Filed Apr. 18, 1962, Ser. No. 183,506
26 Claims. (Cl. 29—401)

The present invention relates to yarn processing machines and more particularly to an apparatus and method for rapidly replacing travelers on the rings of such machines.

In the yarn processing machines to which the present invention relates, i.e., spinning and twisting machines, a plurality of rings are carried by a ring rail and have spindles extending axially therethrough which normally carry yarn winding bobbins upon which the processed yarn is wound. These rings are commonly provided with devices which are known in the art as "travelers" under which yarn is guided during processing. These travelers are relatively small semi-circular or C-shaped in cross section and are usually formed of a hard brittle metal. Opposite ends of the travelers embrace the flange of the ring for being carried thereby. The yarn being processed is normally threaded under one of these travelers prior to being wound upon the bobbin and as the spindle, and hence the bobbin, rotates, the traveler moves in a circular path around the ring to impart twist to the yarn.

It can readily be appreciated that due to the sliding movement of the travelers around the rings the same become worn and must be frequently replaced. Also, the characteristics of the yarn being processed on the machine will dictate the particular type or size of traveler to be used. Therefore, it is quite often necessary to change the travelers on the rings to provide a different type or size of traveler as dictated by the characteristics of the yarn to be processed.

Heretofore, it has been the practice in replacing travelers for any of the aforementioned reasons for an operator to move along the yarn processing machine and to sequentially remove the traveler from each of the rings on at least one side of the machine. This operator usually utilizes a manually operable tool which usually takes the form of a hammer, with which the operator strikes each of the travelers a sharp blow to break the traveler and allow the pieces to fall from the ring. Another conventional tool which is presently in use comprises a hook member which is inserted under the traveler and removes the traveler from the ring when the operator exerts a sharp pull or jerk thereon. Still another conventional apparatus comprises a plier type tool having jaws which are inserted under the traveler and are spread apart to spring the opposite ends of the traveler away from each other so that the traveler is either broken or may be lifted from the ring.

After the operator has removed all of the travelers from the rings of at least one side of the yarn processing machine in one trip therealong, it has heretofore been necessary that he again move along the yarn processing machine or make a second trip therealong and sequentially mount another traveler on each of the rings thereof. In mounting the new travelers on the rings, the operator utilizes a separate traveler mounting tool, of which there are several different types.

Problems have been encountered in the use of the conventional traveler removing devices. In this regard, the conventional traveler removing tools require that the operator manually position the traveler to be removed. Also the tools require that the operator exercise considerable skill in removing the traveler to insure that the ring is not damaged and the yarn is not broken. In the use

of the hammer for removing travelers, the operator must strike the traveler and not the ring since the ring would be pitted or otherwise damaged if struck by the hammer and would have to be replaced. Also, the operator has 5 to utilize considerable skill to insure that he strikes the traveler with sufficient force to break the same without damaging the flange of the ring therebeneath and without breaking the yarn threaded thereunder.

In the use of the hook and plier type tools, the operator 10 must insert the tool into the traveler which is very small and which has the flange of the ring and the yarn therein. It can be appreciated that this was a very tedious and time consuming operation resulting in both mental and physical fatigue of the operator.

15 It can be appreciated that the use of these conventional traveler removing tools results in a high operating cost for the yarn processing machines because these tools require skilled operators who require considerable training and are paid high wages. Also, the replacement of damaged 20 rings and waste caused by broken yarn has increased the maintenance cost and hence the overhead.

The use of these conventional traveler mounting tools is also very time consuming, since the supply of travelers 25 which may be contained thereby is very limited and must be frequently replenished. In these devices, the supply of travelers is normally contained by a bar or wire and the travelers must be manually threaded thereon in stacked relation and in properly oriented position to replenish the supply when the same is depleted. It can 30 readily be appreciated that this operation is very tedious and involves considerable time and effort due to the very small size of the travelers and results in undue mental and physical fatigue on the part of the operator.

Another difficulty which has been encountered in the 35 use of these prior traveler mounting tools is the necessity that the operator manually position the yarn relative to the ring with one hand and mount the new traveler on the ring over the thusly positioned yarn with the other hand. This manner of positioning the yarn and using 40 the traveler mounting tool results in considerable fatigue on the part of the operator, and is also quite time consuming.

It is therefore an object of the present invention to provide 45 an apparatus and method for removing travelers from the rings of a yarn processing machine and for mounting new travelers on the rings, which apparatus may be operated and which method may be performed by an unskilled operator in a single trip along the side of the machine, thus avoiding the necessity of a skilled operator 50 making two separate trips as has been the case heretofore.

It is also an object of this invention to provide a method and apparatus wherein the yarn passing underneath the travelers to be removed may be utilized for positioning the travelers at a predetermined position for ready removal thereof, and wherein each of the new travelers is 55 mounted on the rings with the yarn properly positioned thereunder.

It is a more specific object of this invention to provide 60 an apparatus which can be readily moved from one ring to the next by an operator for quickly replacing travelers on the rings, and wherein the apparatus has a magazine for containing a large number of travelers in loose, disarranged form therein, and wherein means are provided for sequentially feeding the travelers in properly oriented 65 position to a traveler mounting means.

It is also an object of the invention to provide a unitary 70 device for replacing travelers on the rings of textile processing machines wherein the ring rail in which the rings are carried serves to guidingly receive the device and to readily permit the same to be moved along the rail from one ring to the next, and wherein means are provided for

adjusting the traveler replacing components thereof to insure correct positioning thereof relative to the rings to thereby permit the device to readily be used on a wide variety of textile processing machines having varying size rings and ring rails.

It is a further, more specific object of this invention to provide apparatus readily manipulated by an operator for replacing travelers wherein means are provided for positioning the travelers to be removed at a predetermined point on the ring, whereupon means are provided for imparting a blow of predetermined substantially constant force to the travelers for dislodging the same from the rings, and means are provided for positioning new travelers on the rings, while additional means so guide the yarn that the rings are positioned thereover.

Some of the objects of the invention having been stated, other objects will appear as the description proceeds, when taken in connection with the accompanying drawings, in which—

FIGURE 1 is a plan view of the apparatus of the present invention shown in operative position on a portion of the ring rail of a yarn processing machine;

FIGURE 2 is a transverse vertical section taken substantially along line 2—2 in FIGURE 1;

FIGURE 3 is an isometric view looking in the direction of the arrow 3 in FIGURE 1;

FIGURE 4 is an isometric detail of a portion of the apparatus corresponding to that shown in the medial portion of FIGURE 3 with portions broken away for clarity and showing parts thereof in different operational positions;

FIGURE 5 is an enlarged transverse vertical section taken substantially along line 5—5 in FIGURE 1;

FIGURE 6 is a transverse section taken substantially along line 6—6 in FIGURE 5;

FIGURE 7 is an enlarged fragmentary sectional detail of the traveler supplying mechanism of the apparatus shown in FIGURE 1;

FIGURE 8 is an enlarged fragmentary plan detail of the traveler controlling mechanism shown in the medial portion of FIGURE 1 with the cover plate removed and with portions shown in section;

FIGURE 9 is a fragmentary section taken substantially along line 9—9 in FIGURE 8;

FIGURE 10 is a view similar to FIGURE 8 but on a reduced scale showing some of the elements in different operational positions;

FIGURE 11 is a section similar to FIGURE 9 of the control mechanism shown in FIGURE 10;

FIGURE 12 is a view similar to FIGURE 10 showing some of the elements in different operational positions;

FIGURE 13 is a view similar to FIGURE 11 showing the elements in the positions shown in FIGURE 12;

FIGURE 14 is a sectional detail of a portion of the apparatus corresponding to the portion shown in the lower portion of FIGURE 5 with some of the elements shown in different operational positions;

FIGURES 15 through 18 are enlarged fragmentary details of the structure shown in the left hand portion of FIGURE 14 and illustrating the sequential operation of the traveler mounting mechanism;

FIGURE 19 is a vertical section taken substantially along line 19—19 in FIGURE 17;

FIGURE 20 is a transverse section taken substantially along line 20—20 in FIGURE 5;

FIGURE 21 is a transverse section taken substantially along line 21—21 in FIGURE 5; and

FIGURE 22 is a transverse section taken substantially along line 22—22 in FIGURE 14.

Referring now to the drawings and more particularly to FIGURE 1, there is shown a ring rail 23 of a yarn processing machine (not shown). A plurality of rings 24 are mounted on ring rail 23 and have bobbins B shown in phantom lines, extending axially therethrough for winding yarn Y thereon. The yarn Y extends through a yarn

guide 25 mounted on the yarn processing machine (not shown) above the upper end of the bobbin B and then beneath a traveler T₁ disposed on ring 24. Yarn Y then passes to bobbin B onto which the same is wound by rotation of the bobbin by a spindle (not shown) of the yarn processing machine.

The traveler replacing apparatus of the present invention is generally indicated at 30 and comprises a frame 31 which is of a generally inverted U-shaped configuration (FIGURE 3) comprising a horizontally disposed top portion 32 and vertically disposed leg portions 33, 34 depending from opposite ends of top portion 32. Leg portions 33 and 34 each have a substantially horizontally disposed elongate opening 35 formed therethrough adjacent the bottom edge thereof. It is noted that the lower inner corners of leg portions 33 and 34 are cut away to provide horizontally extending shoulders spaced from the bottom edge thereof and portions of reduced thickness in which the openings 35 are formed.

A positioning member 36 is mounted on the bottom portion of each of the leg portions 33 and 34 and depends downwardly therefrom. Positioning members 36 have cut out portions in one side thereof corresponding to the cut out portions of leg portions 33 and 34 except that these cut out portions are in the inner surface of positioning members 36. Positioning members 36 are mounted on the respective leg portions 33, 34 with the cut out portions disposed in mating relation by bolts 37 extending through the elongate openings 35 and penetrating through suitable openings formed in the positioning members 36. Bolts 37 have knurled nuts 37a mounted thereon and nuts 37a have collar portions 37b which are adapted to be moved into engagement with positioning members 36 to releasably clamp the positioning members in adjusted position. It is noted that the positioning members 36 are of a width less than leg portions 33 and 34 such that the leg portions extend outwardly therefrom to provide a shoulder on which apparatus 30 may rest when the same is positioned on ring rail 23.

A bracket member 40 is mounted at opposite ends by any suitable means (not shown) on leg portion 33, 34 and extends therebetween. Bracket member 40 has a longitudinally extending elongate opening 41 formed therein which receives a block 42 having flanges on the sides thereof which contact the lower surface of bracket member 40. A positioning finger 43 is mounted on bracket member 40 by a thumb screw 44 which penetrates through an elongate opening 45 formed in positioning finger 43 and into an internally threaded opening formed in block 42. It is noted that thumb screw 44 and block 42 cooperate to releasably clamp positioning finger 43 to bracket member 40 and elongate openings 41 and 45 allow adjustment of the positioning finger 43 both longitudinally and laterally of bracket member 40. Positioning finger 43 has a bifurcated portion 46 formed at its outer end which includes legs 46a, 46b which are adapted to receive ring 24 on ring rail 23 therebetween to insure that apparatus 30 is correctly positioned relative to ring 24. Positioning members 36 are adjustable in the manner aforementioned to insure correct positioning of the apparatus 30 laterally of ring rail 23 relative to ring 24 and positioning finger 43 insures both longitudinal and lateral alignment of the apparatus relative to ring 24.

A first handle 50 is mounted on the top portion 32 of frame 31 and includes a frame 51 having a relatively flat portion 51a at one end. Portion 51a has a flange 51b thereon which has openings formed therein which are aligned with internally threaded openings formed in the top portion 32 which receive suitable screws 52. Handle 50 includes hand grips 53 which are suitably contoured to fit the hand of an operator and are mounted on opposite sides of frame 51. It is noted that handle 50 serves for manual positioning and holding of the apparatus 30 in operative position on ring rail 23 adjacent ring 24.

Portion 51a of handle frame 51 has a bearing 54 formed

integrally therewith or mounted thereon and projecting upwardly therefrom. A shaft 55 is journaled in bearing 54 at its lower end and extends upwardly therefrom. A collar 56 is fixed to the upper end of shaft 55 by a lock screw 57 for rotation therewith. A yarn tensioning finger 60 is mounted on collar 56 at one end and extends outwardly therefrom and has the outer end portion thereof disposed at an obtuse angle relative to the remaining portion to provide a yarn receiving pocket for receipt of the yarn Y therein. This pocket prevents the yarn Y from sliding off the free end of yarn tensioning finger 60 when the same is moved thereagainst. It is noted that yarn tensioning finger 60 is sufficiently flexible so that the same will bend when the tension in yarn Y reaches a certain point. In this regard, the inner end portion of finger 60 is coiled around shaft 55 to provide greater flexibility to prevent breaking of the yarn.

A pinion gear 61 (FIGURE 2) is drivingly mounted on the lower end of shaft 55 below bearing portion 54 and has the teeth thereof disposed in mating relation with the teeth on a rack 62 slidably mounted in an elongate opening 63 formed in portion 51a of handle 50. Rack 62 terminates in a forked portion 64 which receives the upper end of a trigger 65 and is pivotally connected thereto by a pivot pin 66. Trigger 65 is pivotally mounted on frame 51 of handle 50 by a pivot pin 67 and has a portion extending through a suitable slot formed in frame 51 downwardly to an exposed position when trigger 65 is in inoperative position. This portion of trigger 65 is adapted to be engaged by the finger of the operator using the apparatus for pivoting trigger 65 about its pivot and thereby sliding rack 62 in the elongate opening 63. Trigger 65 has a shoulder 68 formed thereon and a spring member 69 is mounted between shoulder 68 and frame 51 of handle 50 for biasing trigger 65 about its pivot 67 to the inoperative position.

Leg portion 34 has a projection 70 (FIGURE 3) formed on the side thereof adjacent ring 24 when apparatus 30 is in position on ring rail 23. A hammer 71 (FIGURE 5) is pivotally mounted on the lower portion of projection 70 by a pivot pin 72. Hammer 71 has a head portion 71a normally disposed in slightly spaced overlying relation to the upper surface of the flange of ring 24 when the apparatus 30 is in position on ring rail 23. Hammer 71 has a rear portion 71b extending outwardly from pivot pin 72 on the opposite side from head portion 71a for reasons to be presently described. A torsion spring 73 (FIGURE 20) is mounted on pivot pin 72 and is connected at one end to projection 70 and at the other end to hammer 71. A stop pin 74 is mounted on projection 70 and extends outwardly into overlying relation to rear portion 71b of hammer 71. Stop pin 74 serves as a stop to limit the pivotal movement of hammer 71 in a counterclockwise direction (FIGURE 5) about pivot pin 72 or to limit the downward movement of head portion 71a so that head portion 71a travels downwardly a sufficient distance to strike and break a traveler disposed therebeneath but will normally be held in slightly spaced relation to the upper surface of the ring to prevent head portion 71a from contacting the flange of the ring when apparatus 30 is being positioned on ring rail 23. Spring 73 biases hammer 71 about pivot pin 72 toward this normal or first position.

A first yarn positioning member 75 (FIGURE 3) is mounted on projection 70 at one end and has a first portion 75a extending outwardly and rearwardly from projection 70 toward leg portion 33. Yarn positioning member 75 has a second portion 75b smoothly curving forwardly and downwardly from its point of connection with portion 75a and a third portion 75c smoothly curving rearwardly and upwardly from its point of connection with portion 75b and then downwardly at its free end portion. It is noted that the juncture point of portions 75a and 75b defines a yarn receiving pocket which is adapted to receive the vertical portion of the yarn Y therein when the traveler T₁ is removed from the ring 24. It is also noted that the

juncture point of portions 75b and 75c is disposed inwardly of and at a lower elevation than the top of ring 24 and that portion 75c defines a second yarn receiving pocket which is disposed above ring 24 when apparatus 30 is in operative position and is adapted to receive the horizontal portion of the yarn Y therein when the traveler T₁ is removed. It is further noted that portion 75b is of such a configuration that when the tensioned yarn is received in the pocket defined by portion 75c, the vertical portion of the yarn will be cammed into the pocket defined by the juncture point of portions 75a and 75b.

A traveler positioning wand 76 has a substantially horizontal portion 76a which is mounted on the lower surface of top portion 32 and extends outwardly therefrom and a substantially vertical portion 76b extending downwardly from portion 76a to a point at a lower elevation than the top of ring 24. It is noted that wand 76 is positioned on the opposite side of hammer member 71 from projection 70 and closely adjacent thereto and is disposed in engagement with the side ring 24 when apparatus 30 is in position on ring rail 23 to serve as a stop for the traveler T₁ to position the same beneath head portion 71a of hammer 71 for removal thereby.

A second handle 80 (FIGURE 1) including a frame 81 and suitable grips 82 mounted on frame 81 is mounted on leg portion 34 by a pin 83 (FIGURE 5) which penetrates through an elongate opening 84 formed in the frame 81. The elongate opening 84 allows both pivotal and sliding movement of handle 80 relative to leg portion 34. A spring 85 (FIGURE 21) is mounted in a recess formed in frame 81 at one end of elongate opening 84 and engages pin 83 for biasing handle 80 to inoperative position or to the right as seen in FIGURE 1.

An actuating member 90 (FIGURE 5) for actuating hammer 71 is pivotally mounted on frame 81 of handle 80 by a pivot pin 91 for pivotal movement relative thereto. Actuating member 90 includes a projecting portion 90a extending rearwardly from pivot pin 91 and overlying a shoulder 92 formed on the frame 81 of handle 80 which serves to limit the clockwise pivotal movement of actuating member 90. The other end of actuating member 90 is tapered to form a point or end portion 90b with upper and lower converging surfaces. A leaf spring 93 (FIGURE 20) is mounted at one end on frame 81 by a screw 94 and extends outwardly and downwardly therefrom into engagement with the portion 90a of actuating member 90. Spring 93 serves to bias member 90 about pin 91 in a clockwise direction (FIGURE 5) or in such a direction that portion 90a is normally urged into engagement with shoulder 92.

A traveler mounting member 100 (FIGURE 5) is pivotally mounted on frame 81 of handle 80 by a pivot pin 101 for pivotal movement thereabout. A leaf spring 102 is mounted at one end on the upper surface of frame 81 by a screw 103 and engages the upper surface of traveler mounting member 100 at the other end outwardly of pivot pin 101. A second leaf spring 104 is mounted on the bottom surface of frame 81 by a screw 105 and engages the bottom surface of traveler mounting member 100 outwardly of pivot pin 101. It is noted that springs 102 and 104 normally hold member 100 in static position but allow limited movement thereof. Member 100 terminates at its outer end in a head portion 100a which has the under surface thereof contoured substantially the same as the shape of a portion of a traveler. The contoured portion of head portion 100a is adapted to receive a traveler thereagainst to position the same for mounting on ring 24.

A downwardly opening housing 106 is mounted on the head portion 100a of member 100 by screws 107 and has an open bottom end of a width greater than the thickness of head portion 100a. A plate member 110 is slidably mounted in housing 106 and extends downwardly through the open bottom end between one side wall thereof and head portion 100a of traveler mounting member 100. The

upper portion of plate 110 is formed into a laterally extending flange 111 which extends in overlying relation to the top surface of the head portion 100a to limit the downward movement of plate 110. A compression spring 112 is positioned between flange 111 and the top wall of housing 106 to bias plate member 110 downwardly and flange 111 toward engagement with the top surface of head portion 100a. The bottom edge of plate member 110 has a downwardly opening recess 113 formed therein which is adapted to receive the yarn therein when traveler mounting member 100 is moved into engagement with ring 24. It is noted that recess 113 is of a width and depth such that the yarn Y will not be damaged by the pinching action of plate 110 with the flange of ring 24. It is noted that plate 110 is formed of magnetic material such that a traveler positioned in the contoured portion of head portion 100a will be securely held in this position by the magnetic attraction of plate 110.

It is noted that bracket member 40 is spaced rearwardly and downwardly from pivot pin 83 and thereby serves to limit clockwise pivotal movement of handle 80 about pivot pin 83. It is further noted that the weight of the grip portions 82 and frame 81 is such that handle 80 is normally biased thereby into engagement with bracket member 40 with both traveler mounting member 100 and hammer actuating member 90 disposed in the upper or inoperative position.

A second yarn positioning member 115 is mounted at one end on traveler mounting member 100 by a screw 116 and extends outwardly therefrom and terminates in a free end portion. This free end portion is curved upwardly and then downwardly to provide a downwardly opening pocket such that the yarn Y will be moved to the upper most point thereof when the member 115 moves downwardly into engagement with the yarn.

A traveler supply magazine 120 (FIGURE 5) is mounted on a C-shaped bracket 121 which in turn is mounted on the top portion 32 of frame 31 by a pair of screws 122. Magazine 120 comprises an outer wall 123 of an oval configuration in plan, a bottom wall 124, a top cover 125 and an intermediate wall 126 which divides magazine 120 into first and second compartments 127, 128, respectively. The portion 124a of bottom wall 124 defining the bottom of compartment 127 has the center portion thereof disposed at a higher elevation than the outer edges such that the same slopes outwardly and downwardly from the center portion. Compartment 127 is adapted to receive and contain a relatively large supply of travelers in loose, disarranged form and the outwardly sloping bottom wall causes these travelers to slide outwardly toward the outer wall 123 of the compartment 127.

Bottom wall portion 124a has a bearing portion 129 formed at the center portion thereof which has an opening therein which journals the lower end of a shaft 130 for rotation therein. The upper end portion of shaft 130 penetrates through a suitable bearing portion 131 formed on the top cover 125. A knob 132 is mounted on the upper end of shaft 130 for manual rotation thereof.

A pulley 133 is drivingly mounted on the upper portion of shaft 130 on the opposite side of top cover 125 from knob 132. Pulley 133 supports one end of a belt 134, the other end of which is drivingly supported by a drive pulley 135 mounted on the output shaft of an electric motor 136. Electric motor 136 is mounted on the outer wall 123 of compartment 128 and is powered by a pair of dry cell batteries 137 also mounted on wall 123 (FIGURE 6). Batteries 137 are connected together by a wire 138 and to the motor 136 by wires 139, 140 and 141 through a switch 142. Switch 142 has an actuating element 143 extending through a suitable opening formed in the outer wall 123 of the compartment 128 for manual control thereof. It is noted that the intermediate wall 126 of compartment 127 is of a lesser height than outer wall 123 to allow the belt 134 to pass thereover.

A collar 144 (FIGURE 5) is mounted on the lower

portion of shaft 130 for rotation therewith closely adjacent to the bearing portion 129. An agitator member 145 is mounted at one end on collar 144 and has a substantially vertical portion 145a extending downwardly therefrom and a portion 145b which extends substantially parallel to the bottom wall portion 124a of compartment 127 and in close proximity thereto. The outer end of agitator member 145 terminates in close proximity to the outer wall 123 of compartment 127.

The bottom wall portion 124a of compartment 127 is provided with an opening 146 (FIGURE 7) of a configuration substantially the same as the outer configuration of a traveler. A guide member 147 is vertically adjustably mounted on the outer wall 123 of compartment 127 by a screw 148 penetrating through a vertically disposed elongate opening 149 formed in the outer wall 123 of compartment 127. Guide member 147 is normally disposed in vertically spaced relation to the portion of bottom wall portion 124a in which opening 146 is formed a distance slightly greater than the height of a traveler when the same is disposed on its side. A single line of travelers may therefore pass under guide member 147 and sequentially fall through the opening 146 if the same are properly oriented. Guide member 147 also serves the purpose of deflecting all other travelers away from the opening 146. It is noted that improperly oriented travelers in the line of travelers passing under guide member 147 will pass over opening 146 without falling therethrough.

It is further noted that adjustment of guide member 147 relative to bottom wall portion 124a permits travelers of varying height to be properly oriented and fall through opening 146. In this regard, the weight of a traveler of a given internal and external size is varied by varying the height thereof when the traveler is lying on its side. Conventionally, travelers of a given internal and external size may be provided in four or five different heights or weights.

A traveler delivery rod 150 has the upper end thereof disposed within the opening 146 and has a body portion 150a which has a cross sectional configuration and size substantially the same as the inner configuration and size of a traveler and a web portion 150b extending laterally outwardly from the flat portion of body portion 150a. Web portion 150b is of a thickness slightly less than the distance between the inner ends of the in-turned end portions of a traveler. The body portion 150a is adapted to receive the travelers therearound with the in-turned end portions on opposite sides of the web portion 150b to prevent the travelers from rotating around the body portion 150a and to thereby deliver the travelers in properly oriented position.

The upper end of the web portion 150b is connected to the medial portion of the flat portion of the walls of opening 146 corresponding to the in-turned end portions of a traveler to position body portion 150a at substantially the same height as the bottom wall portion 124a of compartment 127. It is noted that when a traveler is moved along bottom wall portion 124a by agitator 145 the same will be moved into overlying relation to the upper end of traveler delivery rod 150, and if the traveler is in properly oriented position, the same will drop by gravity onto rod 150.

Traveler delivery rod 150 terminates in a free end portion at its lower end in close proximity to the contoured portion of head portion 100a of traveler mounting member 100 such that the travelers will slide off the lower end of rod 150 with one side thereof against plate 110 and a portion thereof in the contoured portion of head portion 100a (FIGURE 3). Delivery rod 150 extends through a traveler control mechanism 151 which controls the delivery of travelers to traveler mounting member 100.

Traveler control mechanism 151 (FIGURE 7) comprises a housing 152 including bottom, side and end walls

152a, 152b, and 152c, respectively, and a top closure plate 153 which is removably mounted on the housing 152 by suitable screws 154. Closure plate 153 and bottom wall 152a have suitable openings formed therein of a larger diameter than rod 150 and any travelers disposed thereon such that the travelers may pass freely through these openings on rod 150.

A first slide 155 (FIGURES 8-13) is slidably mounted in housing 152 and is of a length substantially equal to the width of the bottom wall 152a and of a height substantially the same as the height of side walls 152b. The end wall 152c adjacent slide 155 and one end of slide 155 have recesses 156, 157, formed therein, respectively, which receive opposite ends of a compression spring 160 to bias slide 155 toward rod 150. Slide 155 has a portion thereof cut away to form a flange 161 of reduced thickness at the bottom thereof. Flange 161 has a recess 162 formed therein of a configuration substantially the same as the configuration of the portions of body portion 150a extending outwardly on opposite sides of web portion 150b such that this portion of body portion 150a may be received in recess 162 with the edge of flange 161 abutting the side of web portion 150b. It is noted that slide 155 is normally positioned with flange 161 engaging rod 150 and with a stack of travelers T₂ supported thereby.

A second slide 163 is slidably mounted in housing 152 on the opposite side of rod 150 from slide 155. Slide 163 has an elongate opening 164 formed therein into which penetrates a projection 165 formed on the closure plate 153. Projection 165 has a recess 166 formed therein which receives one end of a compression spring 167 therein and the opposite wall of opening 164 has a recess 168 formed therein which receives the other end of spring 167. It is noted that spring 167 serves to bias slide 163 away from rod 150. Slide 163 has a portion 170 extending through an opening formed in the end wall 152c and which mounts an actuating member 171 at its other end. Actuating member 171 is disposed adjacent handle 50 and is adapted to be engaged by the operator's thumb to move slide 163 toward rod 150 against the action of the spring 167.

A third slide 172 is slidably mounted in an elongate recess formed in the end of slide 163 adjacent rod 150. Slide 172 is formed in two sections, i.e., a rear section 172a and a forward section 172b. Rear section 172a is of a width substantially the same as the distance between side walls 152b and a height substantially the same as the height of side walls 152b. Forward section 172b is of substantially the same width but of lesser height than rear section 172a and has a dovetail key portion mounted in a cooperating vertically disposed dovetail groove formed in rear section 172b. Forward section 172b is thereby mounted for vertical adjustment on rear section 172a but slidably moves therewith. The dovetail key portion of forward section 172b has a vertically disposed internally threaded opening therethrough which matingly receives a threaded shaft 173. Shaft 173 penetrates through elongate openings formed in bottom wall 152a and closure plate 153, respectively, which allow shaft 173 to move toward and away from traveler delivery rod 150.

A washer 174 is mounted on the lower end of shaft 173 on the opposite side of bottom wall 152a from slide 172 to journal shaft 173 for rotation in the elongate opening formed in bottom wall 152a. A knob 175 is drivingly mounted on the upper end of shaft 173 by a set screw 176 on the opposite side of closure plate 153 from slide 172 for manual rotation of shaft 173. Knob 175 has a flange 175a at its bottom end which has graduations thereon which cooperate with a base mark or pointer (not shown) on closure plate 153 to visually indicate the adjusted position of forward portion 172b.

Forward section 172b has a portion thereof cut away to form a flange 177 adjacent the upper surface thereof.

Flange 177 has a recess 180 cut therein of substantially the same configuration as recess 162. A compression spring 181 is mounted between slide 163 and the rear section 172a of slide 172 for biasing slide 172 toward rod 150. The movement of slide 172 relative to slide 163 is limited by a pair of inturned flanges 182 formed on the end of slide 163 adjacent traveler delivery rod 150, which flanges extend into the mouth of the recess, formed in slide 163. It is noted that flange 177 on the forward section 172b of slide 172 is disposed at a higher elevation than flange 161 relative to rod 150 a distance substantially equal to the height of a traveler resting on its side. It is further noted that the vertical distance between flange 177 and flange 161 is adjustable in the manner set forth above to permit control mechanism 151 to be used with travelers of varying heights.

In operation, when it is desired to replace the travelers T₁ disposed on rings 24 by new travelers T₂, apparatus 30 is positioned on ring rail 23 in operative position relative to the first ring 24 thereon (FIGURES 1 and 3). To insure correct lateral alignment of apparatus 30 with the rings 24, the positioning members 36 are adjusted relative to the leg portions 33 and 34 in accordance with the particular size or width of the ring rail 23. Further to insure correct longitudinal and lateral alignment of apparatus 30 with the rings 24, the positioning finger 43 is adjusted longitudinally and laterally of bracket member 40 in accordance with the size or diameter of the rings 24 mounted on ring rail 23.

As noted above, apparatus 30 is carried and held in position by an operator who grasps handle 50 and manually positions the apparatus on ring rail 23 and holds the same in operative position. When the apparatus 30 is in operative position and correctly positioned relative to the first ring 24, the traveler T₁ mounted on ring 24 is moved to a predetermined point thereon by pivoting trigger 65 about its pivot 67 against the action of spring 69 (FIGURE 2). Trigger 65 slidably moves rack 62 and thereby rotates pinion 61. Pinion 61 rotates shaft 55 which moves yarn tensioning finger 60 into engagement with the yarn Y above yarn guide 25. Finger 60 applies tension to the yarn and causes partial unwinding thereof from the bobbin B. Traveler T₁ is thereby moved around ring 24 until the same engages the side of head portion 71a of hammer 71 (FIGURE 20). It is noted that yarn tensioning finger 60 preferably moves through substantially the same arc regardless of the initial position of traveler T₁ on ring 24 but that the flexible nature thereof prevents the same from breaking the yarn when traveler T₁ is initially positioned only a short distance from hammer 71.

When the traveler T₁ thusly positioned and the yarn Y still under tension, a new traveler T₂ is released by traveler control mechanism 151 by moving actuating member 171 (FIGURE 1). This moves slide 163 (FIGURES 8-13) of traveler control mechanism 151 toward traveler delivery rod 150 against the action of spring 167. The end of slide 163 adjacent rod 150 is moved into engagement with slide 155 which is in engagement with rod 150. It is noted that flange 161 on slide 155 normally has a stack of new travelers T₂ resting thereon. As slide 163 is moved into engagement with slide 155, flange 177 on the forward section 172b of slide 172 is moved into engagement with the stack of travelers resting on flange 161 and is moved between the bottom and penultimate travelers in the stack. Further movement of slide 163 moves slide 155 out of engagement with rod 150 and thereby moves flange 161 out of underlying relation to the bottom traveler. This allows the bottom traveler to fall downwardly through the opening in the bottom wall 152a of housing 152 and to travel along rod 150 to head portion 100a of traveler mounting member 100 (FIGURE 3). The remaining travelers in the stack are supported by flange 177 until flange 161 is again moved into underlying relation thereto.

When the traveler is delivered to head portion 100a,

the same is positioned in the contoured portion thereof and against plate 110 by the magnetic attraction thereof (FIGURE 15). The operator then releases pressure on the actuating member 171 and allows spring 167 to move slide 163 toward the retracted position. As slide 163 moves toward the retracted position, spring 160 moves slide 155 into contact with traveler delivery rod 150 with a portion of the rod disposed in the recess 162 and flange 161 in underlying relation to the stack of travelers on rod 150. It is noted that spring 181 maintains the forward section 172b of slide 172 in engagement with traveler delivery rod 150 until flange 161 is moved into engagement with the rod 150. With the slide 155 in engagement with rod 150, slide 163 continues its movement to the retracted position and thereby moves the forward section 172b of slide 172 out of engagement with rod 150. This allows the stack of travelers to slide downwardly along rod 150 until the same come to rest on flange 161 of slide 155.

If the stack of travelers disposed on rod 150 is depleted beyond a predetermined number, the operator replenishes the stack by rotating shaft 130 (FIGURE 5) either by the knob 132 or closing switch 142 through actuating element 143 to allow the battery powered motor 136 to rotate the shaft 130 through pulleys 135, 133 and belt 134. Rotation of shaft 130 rotates agitator element 145 in compartment 127 to move the travelers disposed therein over the bottom wall portion 124a (FIGURE 7). Some of the travelers are moved beneath guide member 147 and those travelers which are properly oriented fall through opening 146 in surrounding relation to the body portion 150a of rod 150. It is noted that the operator may position as many travelers on the rod as desired within the limits dictated by the length of rod 150 from the traveler control mechanism 152 and the bottom wall 124 of the magazine 120.

With a traveler T₂ correctly positioned on the head portion 100a of traveler mounting member 100, the operator grasps handle 80 and slides the same forwardly toward ring 24 against the action of spring 85. This sliding movement of the handle 80 positions the tapered point portion 90b of actuating member 90 in overlying relation to the rear portion 71b of hammer 71. Also, this forward sliding movement of handle 80 positions the head portion 100a of traveler mounting member 100 in overlying relation to ring 24 and slightly forwardly thereof such that pivotal movement of traveler member 100 will move the head portion 100a into traveler mounting position.

The operator then lifts upwardly on handle 80 and thereby pivots the same about pivot pin 83. This pivotal movement moves the tapered end portion 90b of actuating member 90 into engagement with the top surface of rear portion 71b of hammer 71. Further pivotal movement of the handle 80 moves hammer 71 in a clockwise direction about pivot pin 72, as seen in FIGURE 5, and thereby moves the head portion 71a thereof upwardly from the normal or first position wherein the same is in close proximity to the upper surface of ring 24 (FIGURE 4). When the head portion 71a moves upwardly a sufficient distance, the tension in the yarn Y moves the traveler T₁ beneath head portion 71a and into engagement with traveler positioning wand 76.

Still further pivotal movement of handle 80 moves hammer actuating member 90 and hammer 71 to such a relative position that the tapered end portion 90b of actuating member 90 will be moved off of the rear portion 71b of hammer 71. When this occurs, spring 73 will quickly return hammer 71 to its normal or first position and the head portion 71a will deliver a sharp blow to the traveler T₁ disposed therebeneath. This sharp blow will fracture or break the traveler causing the pieces thereof to fall from the ring 24.

When the traveler T₁ is thusly removed from the ring, the yarn Y that was threaded therebeneath is captured by first yarn positioning member 75 (FIGURE 21) and is held closely adjacent to the ring flange by the pocket

defined by portion 75c thereof and extends upwardly into the pocket defined by the juncture point of portions 75a and 75b. Second yarn positioning member 155 is moved into engagement with the yarn Y at a point spaced from first yarn positioning member 75 upon further pivotal movement of handle 80 (FIGURE 22). The configuration of this member is such that the yarn Y is cammed into the highest point of the pocket defined by the end portion thereof which is normally disposed immediately above the flange of ring 24. The yarn Y is thusly positioned on top of the flange of ring 24 and is held in this position so that, when the traveler T₂ is mounted on ring 24, the yarn is threaded thereunder.

Plate 110 is then moved into contact with the flange of ring 24 and the yarn Y is received in the recess 113 (FIGURES 14-19). Further downward movement of head portion 100a of traveler mounting member 100 moves plate 110 upwardly against the action of spring 112. Due to the positioning of head portion 100a slightly forward of the flange of ring 24, the traveler T₂ is moved downwardly in such a position relative to ring 24 such that the inner portion of the flange of ring 24 enters the space between the in-turned end portions of the traveler such that the in-turned end portion on one side of the traveler is hooked under the inner portion of the flange on ring 24. Further downward and rearward movement of the head portion 100a of traveler mounting member 100 causes the other in-turned end portion of the traveler to engage the top surface of the flange of ring 24 and to be cammed away from the end portion hooked under the inner portion of the flange until the other end portion moves past the outer portion of the flange of ring 24 and snaps into position thereunder.

With traveler T₂ thusly mounted on the ring in superposed relation to the yarn Y, the operator moves handle 80 in the opposite direction about the pivot 83 and thereby moves the head portion 100a of traveler mounting member 100 and plate 110 out of engagement with the thusly mounted traveler. With traveler mounting member 100 out of engagement with the traveler, the operator releases trigger 65 and spring 69 returns the same to the original position. Rack 62 is thereby returned to the original position which rotates shaft 55 and yarn tensioning finger 60 back to the original position with the yarn tensioning finger out of engagement with the yarn Y.

The replacement of the traveler on the first ring 24 has now been completed. The operator then moves apparatus 30 to the next adjacent ring 24 and the operation is repeated.

It is therefore apparent that a novel apparatus and method for replacing travelers on rings of yarn processing machines are provided wherein the travelers are rapidly removed and replaced in one trip of an operator along the side of a textile machine and whereby the yarn is positioned so that the new traveler is mounted on the ring with the yarn correctly positioned thereunder.

In the drawings and specification there has been set forth a preferred embodiment of the invention and, although specific terms are employed, they are used in a generic and descriptive sense only and not for purposes of limitation, the scope of the invention being defined in the claims.

I claim:

1. Apparatus for replacing travelers on rings of a yarn processing machine, said apparatus comprising
  - (a) frame means adapted to be positioned on the yarn processing machine adjacent the rings,
  - (b) means carried by said frame means for removing a traveler disposed on the ring of the yarn processing machine, and
  - (c) means carried by said frame means and operatively associated with said traveler removing means for mounting a new traveler on the ring.
2. Apparatus for use with a yarn processing machine having rings with travelers disposed thereon and nor-

normally having yarns threaded under the travelers, said apparatus comprising

- (a) frame means adapted to be positioned on the yarn processing machine adjacent the rings,
- (b) means carried by said frame means for positioning a traveler disposed on a ring at a predetermined point thereon,
- (c) means carried by said frame means adjacent said traveler positioning means for removing the thusly positioned traveler from the ring, and
- (d) means carried by said frame means and operatively associated with said traveler removing means for mounting a new traveler on the ring.

3. Apparatus for use with a yarn processing machine having rings with travelers disposed thereon and normally having yarns threaded under the travelers, said apparatus comprising

- (a) means for removing a traveler disposed on the ring,
- (b) means disposed adjacent said traveler removing means for positioning the yarn threaded under the traveler in superposed relation to the ring, and
- (c) means operatively associated with said traveler removing means for positioning a new traveler on the ring over the thusly positioned yarn.

4. Apparatus for use with a yarn processing machine having rings and travelers disposed on the rings having yarns threaded thereunder, said apparatus comprising

- (a) means for removing the traveler disposed on each of the rings,
- (b) means for mounting a new traveler on each of the rings, and
- (c) means interconnecting said traveler removing means and said traveler mounting means comprising manually operable means for actuating said traveler removing means and said traveler mounting means.

5. The structure recited in claim 4 wherein said means for removing the travelers comprises a movable hammer which is adapted to strike the travelers on the rings a blow of sufficient force to break the same.

6. The structure recited in claim 5 including spring means biasing said movable hammer toward a first position wherein said hammer is in contact with the ring when the apparatus is in operative position.

7. Apparatus for use with a yarn processing machine having rings with travelers disposed thereon and normally having yarns threaded under the travelers, said apparatus comprising

- (a) frame means adapted to be positioned on said yarn processing machine adjacent the rings,
- (b) a hammer pivotally mounted on said frame means and adapted to strike the travelers on the rings a blow of sufficient force to break the same,
- (c) spring means operatively connected to said hammer to bias said hammer toward a first position wherein said hammer is in close proximity to the upper surface of the ring when said frame means is in operative position on said yarn processing machine,
- (d) means carried by said frame means for mounting a new traveler on the ring, and
- (e) manually operable means connected to said traveler mounting means and engageable with said hammer for moving said hammer about its pivot to a second position spaced from said first position and against the action of said spring means while moving said traveler mounting means toward said ring, said manually operable means being disengaged from said hammer when said hammer reaches said second position to allow said spring means to quickly return said hammer to the first position, said manually operable means then moving said traveler mounting means into position to mount a new traveler on the rings.

8. Apparatus for use with a yarn processing machine having rings with travelers disposed thereon and nor-

75 mally having yarns threaded under the travelers, said apparatus comprising

- (a) frame means adapted to be positioned on said yarn processing machine adjacent the rings,
- (b) means carried by said frame means for removing a traveler disposed on the ring,
- (c) a traveler mounting member mounted on said frame means for movement between a traveler receiving position and a traveler mounting position wherein said traveler mounting member is in contact with the ring for mounting a new traveler thereon, and
- (d) manually operable means carried by said frame means and operatively connected to said traveler removing means for actuating the same to remove the traveler disposed on the ring, said manually operable means being also operatively connected to said traveler mounting member for moving the same from said traveler receiving position to said traveler mounting position.

9. The structure recited in claim 8 wherein said traveler mounting member includes a contoured portion of a configuration substantially the same as the outer configuration of a portion of a traveler and is adapted to receive this portion of a traveler therein, and including a movable plate member carried by said traveler mounting member and constructed of magnetic material for attracting and releasably holding a traveled in position on said traveler mounting member for mounting on the ring.

10. Apparatus for use with a yarn processing machine having rings with travelers disposed thereon, said apparatus comprising

- (a) frame means adapted to be positioned on said yarn processing machine adjacent the rings,
- (b) means carried by said frame means for removing a traveler disposed on the ring,
- (c) means carried by said frame means and operatively associated with said traveler removing means for mounting a new traveler on the ring, and
- (d) traveler supplying means mounted on said frame means and operatively associated with said traveler mounting means for sequentially delivering travelers thereto in properly oriented position for mounting on the ring.

11. The structure recited in claim 10 wherein said traveler supplying means comprises a magazine adapted to contain a supply of travelers in loose disarranged form, and traveler delivery means communicating with the interior of said magazine and operatively associated with said traveler mounting means for sequentially delivering travelers from said magazine to said traveler mounting means.

12. The structure recited in claim 11 wherein said magazine is carried by said frame means at a higher elevation than said traveler mounting means and wherein said traveler delivery means comprises a traveler delivery rod having one end communicating with the interior of said magazine and the other end positioned closely adjacent to said traveler mounting means for delivering travelers thereto, and traveler control means disposed intermediate the ends of said traveler delivery rod for effecting sequential delivery of travelers to said traveler mounting means.

13. Apparatus for use with a yarn processing machine having rings with travelers disposed thereon, said apparatus comprising

- (a) frame means adapted to be positioned on said yarn processing machine adjacent the rings,
- (b) means carried by said frame means for removing a traveler disposed on the ring,
- (c) means carried by said frame and operatively associated with said traveler removing means for mounting a new traveler on the ring,
- (d) a magazine mounted on said frame means at a

- higher elevation than said traveler mounting means and adapted to contain a large supply of travelers in loose, disarranged form.
- (e) a traveler delivery rod mounted on said magazine at one end and having the other end positioned closely adjacent to said traveler mounting means, said one end of said traveler delivery rod communicating with the interior of said magazine and being adapted to receive travelers thereon from said magazine, 5
- (f) means disposed in said magazine for positioning 10 travelers on said traveler delivery rod in properly oriented position for delivery to said traveler mounting means, and
- (g) traveler control means disposed intermediate the ends of said traveler delivery rod for effecting sequential delivery of travelers to said traveler mounting means.

14. The structure recited in claim 13 wherein said magazine includes side and bottom walls and said means for positioning travelers on said traveler delivery rod 20 comprises an agitator rotatably mounted within said magazine for moving the travelers disposed therein around within the magazine over the bottom wall thereof, the bottom wall of said magazine having an opening therein of a configuration substantially the same as the exterior 25 configuration of a traveler so that a properly oriented traveler may fall therethrough, said traveler delivery rod having one end disposed in said opening in the bottom wall of said magazine, and guide means carried by the side wall of said magazine and spaced a distance above 30 the portion of the bottom wall having said opening therein to correspond to the height of a traveler disposed on its side such that only a single traveler may pass thereunder at a time.

15. The structure recited in claim 13 wherein said traveler control means comprises a first slide having a traveler delivery rod contacting portion, said first slide being movable from a first position in which the rod contacting portion thereof is positioned in engagement with said rod and serves to support the travelers disposed thereon in stacked relation to a second position in which the rod contacting portion is spaced from said rod and out of underlying relation to the stack of travelers disposed thereon, a second slide having a traveler delivery rod contacting portion, said second slide being movable from a first position in which the rod contacting portion thereof is disposed out of engagement with said rod to a second position in which the rod contacting portion is in engagement with said rod, the traveler delivery rod contacting portion of said second slide being disposed at a higher elevation than the rod contacting portion of said first slide a distance substantially equal to the height of a traveler in the stack of travelers disposed on said traveler delivery rod, and means for moving said second slide from said first position to said second position so that the rod contacting portion thereof engages the traveler delivery rod between the penultimate and last travelers in the stack of travelers disposed thereon and supported by the rod contacting portion of said first slide and for sequentially moving said first slide from said first position to the second position to move the rod contacting portion thereof from beneath said last traveler to allow the same to be delivered by said traveler delivery rod to said traveler mounting means while the remaining travelers in the stack are retained by the rod contacting portion of said second slide, said latter means then returning said first slide from the second position to the first position and sequentially returning the second slide from the second position to the first position.

16. Apparatus for use with a yarn processing machine having rings with travelers disposed thereon, said apparatus comprising

- (a) frame means adapted to be positioned on said yarn processing machine adjacent the rings,
- (b) means carried by said frame means for removing 70

- a traveler disposed on the rings of the yarn processing machine,
- (c) means carried by said frame means and operatively associated with said traveler removing means for mounting a new traveler on the ring,
- (d) a magazine mounted on said frame means at a higher elevation than said traveler mounting means and adapted to contain a large supply of travelers in loose, disarranged form, said magazine including side and bottom walls with said bottom wall having an opening therein of a configuration substantially the same as the exterior configuration of a traveler so that a traveler may fall therethrough when properly oriented,
- (e) a traveler delivery rod having one end thereof disposed in the opening in the bottom wall of said magazine and the other end disposed closely adjacent to the traveler mounting means for delivering travelers from the magazine to the traveler mounting means, said traveler delivery rod comprising a body portion having a cross-sectional configuration substantially the same as the internal configuration of a traveler, and a web portion extending outwardly from the flat portion of the body portion and of a thickness slightly less than the distance between the spaced inturned end portions of a traveler, the upper end of said web portion being mounted on the bottom wall portion defining the flat side of the opening in the bottom wall of said magazine,
- (f) an agitator rotatably mounted within said magazine in closely spaced relation to the upper surface of the bottom wall for moving the travelers in the magazine over the bottom wall,
- (g) a guide member adjustably mounted on the side wall of the magazine in overlying relation to the portion of the bottom wall having the opening therein, said guide member being spaced from said bottom wall a distance corresponding to the height of a traveler disposed on its side and adjustment of said guide member allowing the distance between the guide member and the bottom wall to be varied to accommodate travelers of varying height, said guide member and bottom wall cooperating to allow only a single traveler to pass therebetween at a time so that properly oriented travelers may fall through the opening in surrounding relation to the body portion of the traveler delivery rod with the inturned end portions thereof disposed on opposite sides of the web portion, and
- (h) traveler control means disposed intermediate the ends of said traveler delivery rod and comprising
- (1) a first slide having a traveler delivery rod contacting portion and being movable from a first position in which the rod contacting portion is in engagement with said rod to support the travelers disposed thereon in stacked relation and a second position in which the rod contacting portion is out of engagement with said rod and out of underlying relation to the travelers disposed thereon,
- (2) a second slide having a traveler delivery rod contacting portion and being movable from a first position in which the rod contacting portion is out of engagement with said traveler delivery rod to a second position in which the rod contacting portion is in engagement with said traveler delivery rod, the rod contacting portion of said second slide being disposed at a higher elevation than the rod contacting portion of said first slide a distance substantially equal to the height of one traveler in the stack of travelers disposed on said delivery rod, the delivery rod contacting portion of said second slide being adjustably mounted on the remaining portion of said second slide so that the elevation thereof

relative to the rod contacting portion of said first slide may be varied to accommodate travelers of varying height, and

(3) means for moving said second slide from said first position to said second position to move the rod contacting portion thereof into engagement with said delivery rod between the penultimate and last travelers in the stack of travelers disposed on said rod and for sequentially moving said first slide from said first position to the second position to move the rod contacting portion thereof from beneath said last traveler to allow the same to move along said rod to said traveler mounting means, said latter means then returning said first slide from the second position to the first position to move the rod contacting portion thereof into engagement with said rod and sequentially returning said second slide from the second position to the first position to allow the stack of travelers to move downwardly onto the rod contacting portion of said first slide.

17. Apparatus for use with a yarn processing machine having a ring rail, rings carried by said ring rail and travelers disposed on the rings, said apparatus comprising

- (a) frame means adapted to be positioned on said ring rail adjacent the rings,
- (b) means carried by said frame means for removing a traveler disposed on the ring of the yarn processing machine,
- (c) means carried by said frame means and operatively associated with said traveler removing means for mounting a new traveler on the ring, and
- (d) positioning means adjustably carried by said frame means and engageable with the ring rail and rings for correctly positioning and alining said traveler removing means and said traveler mounting means relative to the rings, adjustment of said positioning means relative to said frame means permitting the traveler removing means and traveler mounting means to be correctly positioned and alined with rings of varying size and ring rails of varying width.

18. The structure recited in claim 17 wherein said positioning means includes a bifurcated member which is adapted to engage the outer surface of the rings and is adjustably mounted on said frame means to position and aline the traveler removing means and traveler mounting means with varying diameter rings.

19. Apparatus for use with a yarn processing machine having rings with travelers disposed thereon, said apparatus comprising

- (a) frame means adapted to be positioned on said yarn processing machine adjacent the rings,
- (b) a hammer pivotally mounted on said frame means for movement between a first position wherein said hammer is in close proximity to the upper surface of said rings when said frame means is in operative position on said yarn processing machine, and a second position spaced from said first position,
- (c) spring means operatively connected to said hammer for biasing the same toward said first position, and
- (d) manually operable means carried by said frame means and engageable with said hammer for moving said hammer from said first position to said second position, said manually operable means being disengaged from said hammer when the same reaches said second position to allow said spring means to return said hammer to the first position with sufficient force to break any traveler disposed in the path of travel thereof.

20. Apparatus for use with a yarn processing machine having rings with travelers disposed thereon, said apparatus comprising

- (a) frame means adapted to be positioned on said yarn processing machine adjacent the rings,
- (b) means carried by said frame means and movable between a traveler receiving position and a position in engagement with said rings for mounting a traveler on the rings,
- (c) a magazine carried by said frame means and adapted to contain a large supply of travelers in loose, disarranged form,
- (d) a traveler delivery rod having one end communicating with the interior of said magazine and adapted to receive travelers therefrom and having the other end thereof operatively associated with said traveler mounting means for delivering travelers thereto, and
- (e) traveler control means disposed intermediate the ends of said rod for controlling the sequential delivery of travelers to said traveler mounting means.

21. A method of replacing travelers on the rings of a yarn processing machine having a yarn threaded under the traveler disposed on the ring, said method comprising the steps of

- (a) positioning the traveler at a predetermined point on the ring,
- (b) removing the traveler on the ring while controlling the yarn threaded thereunder to position the yarn in superposed relation to the ring, and
- (c) mounting a new traveler on the ring over the thusly positioned yarn.

22. A method of replacing travelers on the rings of a yarn processing machine having a yarn threaded under the traveler disposed on each of the rings, said method comprising the steps of

- (a) positioning the traveler at a predetermined point on the initial ring,
- (b) removing the traveler on this ring,
- (c) mounting a new traveler on this ring while threading the yarn thereunder, and
- (d) repeating the above steps for each of the remaining rings of the yarn processing machine in succession.

23. A method of replacing travelers on the rings of a yarn processing machine, said machine having a bobbin extending axially through each of the rings for winding yarn thereon, the yarn normally extending outwardly from the bobbin under the traveler disposed on the ring and then upwardly therefrom to a point above the bobbin, said method comprising the steps of

- (a) tensioning the yarn on the opposite side of the traveler from the bobbin at a point above the bobbin to unwind a portion thereof from the bobbin and to cause the traveler to move around the ring,
- (b) stopping the traveler at a predetermined point on the ring,
- (c) removing the traveler from the ring while controlling the yarn threaded thereunder to position the yarn in superposed relation to the ring, and
- (d) mounting a new traveler on the ring over the thusly positioned yarn.

24. A method of replacing travelers on the rings of a yarn processing machine, said machine having a bobbin extending axially through each of the rings for winding yarn thereon, the yarn normally extending outwardly from the bobbin under the traveler disposed on the ring and then upwardly therefrom through a thread guide to a set of drafting rolls, said method comprising the steps of

- (a) tensioning the yarn above the thread guide to unwind a portion thereof from the bobbin and to thereby cause the traveler to move around the ring,
- (b) stopping the traveler at a predetermined point on the ring,
- (c) striking the traveler a sharp blow of sufficient force to fracture the same to remove the traveler from the ring and to release the yarn threaded thereunder,
- (d) controlling the thusly released yarn to position the same in superposed relation to the ring,

(e) mounting a new traveler on the ring over the thusly positioned yarn, and

(f) repeating the above steps for each of the remaining rings of the yarn processing machine in succession.

25. A method of replacing travelers on rings of a yarn processing machine, said yarn processing machine having a bobbin extending axially through each of the rings for the winding of a yarn on the bobbin, the yarn normally extending outwardly from the bobbin, under the traveler disposed on the ring and then upwardly therefrom to a point above the bobbin, said method comprising the steps of

(a) tensioning the yarn on the side of the traveler remote from the bobbin at a point above the bobbin while moving the traveler around the ring,

(b) interposing a stop in the path of the traveler at a predetermined point on the ring to stop the traveler at the predetermined point and to thereby position the same for removal,

(c) striking the thusly positioned traveler a sharp blow to break the traveler and remove the same from the ring while maintaining the yarn under tension,

(d) positioning the tensioned yarn in superposed relation to the ring upon removal of the traveler, and

(e) mounting a new traveler on the ring over the thusly positioned yarn.

26. Apparatus for replacing travelers on the rings of a yarn processing machine, said yarn processing machine having a bobbin extending axially through each of the rings for the winding of yarn on the bobbin, the yarn normally extending outwardly from the bobbin under the traveler disposed on the ring and then upwardly therefrom to a point above the bobbin, said apparatus comprising

(a) tensioning means movable into engagement with the yarn on the side of the traveler remote from the bobbin and at a point above the bobbin for tensioning the yarn to move the traveler around the ring,

(b) stop means disposed adjacent the ring and in the path of the traveler for stopping the traveler at a predetermined point on the ring to position the same for removal,

(c) means disposed adjacent said stop means for striking the thusly positioned traveler a sharp blow to break the same and to thereby remove the traveler from the ring,

(d) means disposed adjacent said stop means and cooperating with said tensioning means for positioning the yarn tensioned by said tensioning means in superposed relation to the ring, and

(e) means disposed adjacent said yarn positioning means (d) for mounting a new traveler on the ring over the thusly positioned yarn.

UNITED STATES PATENT OFFICE
CERTIFICATE OF CORRECTION

Patent No. 3,191,284

June 29, 1965

Edward E. Eurey

It is hereby certified that error appears in the above numbered patent requiring correction and that the said Letters Patent should read as corrected below.

Column 6, line 62, after "limited" insert -- pivotal --;
column 12, line 67, for "pressing" read -- processing --;
column 14, line 28, for "traveled" read -- traveler --.

Signed and sealed this 18th day of January 1966.
